TEMPERATURE CONTROL DEVICE

Wallace J. Ettinger, Chicago, Ill., assignor to
 Edison General Electric Appliance Company,
 Inc., Chicago, Ill., a corporation of New York

Application September 26, 1939, Serial No. 296,611

14 Claims. (Cl. 200—139)

This invention relates to a control device for controlling an electric circuit in accordance with temperature changes and more specifically relates to a control device which is adapted to be actuated with a snap action.

More specifically, this invention relates to temperature control devices of the type having a thermal element arranged to move in accordance with temperature changes and resilient means engaging the thermal element so as to effect its movement with a snap action, the movement of the thermal element being utilized to actuate switch means comprising fixed and movable contacts.

It is an object of this invention to provide in control devices of this type new and improved means for maintaining the contact pressure between the fixed and movable contacts of the control device until the thermal means are moved with a snap action.

It is another object of my invention to provide in control devices of the aforementioned type new and improved means for maintaining a substantially constant closing force for closing the electrical contacts whereby good electrical contact is made.

It is a further object of my invention to provide improved means for actuating a plurality of contacts with a snap action in accordance with movement of the thermal element.

It is a more specific object of my invention to provide a control device having a member which is pivotally mounted independently of the thermal element for operating the circuit controlling means and to provide new and improved means for transmitting the movement of the thermal element to the control member.

A further object of my invention is to provide a temperature control device having a new and improved arrangement of elements characterized by its improved switch action, its increased sensitivity, its ruggedness, and its relatively low manufacturing cost.

Further objects and advantages of my invention will become apparent as the following description proceeds, and the features of novelty which characterize my invention will be pointed out with particularity in the claims annexed to and forming a part of this specification.

For a more complete understanding of my invention, reference should be had to the accompanying drawing in which Fig. 1 is a plan view partially broken away of my improved temperature control device; Fig. 2 represents a vertical section taken on the line 2—2 in Fig. 1 showing

the elements of my device in one operative position; Fig. 3 is a vertical section similar to Fig. 2 showing the elements in a different operative position; Fig. 4 is a plan view of the control member showing details of its construction; Fig. 5 is a plan view of the temperature responsive member used in my improved control device; and Fig. 6 is a plan view showing details of the transmission member between the control member and the bimetallic member.

Referring to the drawing, this invention has been shown in one form as applied to a temperature responsive device intended to be used to control rather large currents such as those encountered in a domestic hot water heating system, but it is to be understood that it is applicable to thermostats to be used in systems where the currents are relatively small and also in systems wherein the currents handled are considerably larger than those encountered in domestic hot water systems.

As shown in Figs. 1, 2 and 3, the temperature control device comprises a base or supporting member 10 formed from a suitable metallic material such as steel. Mounted on one end of the base member 10 is an insulating block 11 which is adapted to form an end wall of the control device and is provided with recesses and supporting flanges so as to form a terminal block 12 as will more fully appear hereinafter. The block 11 is made of some suitable insulating material, such as a suitable phenolic condensation product, and is firmly attached to the base member 10 by means of a plurality of screws 13 and 14.

Arranged between the base member 10 and the insulating block 11 and extending longitudinally of the base member is a suitable temperature responsive member 15 which is firmly held in position by means of a pair of rivets 16 located on opposite sides of the screw 13, only one of the rivets being shown in the drawing. The temperature responsive member comprises a relatively thin, resilient, bimetallic blade or strip made of two strips of metal having dissimilar temperature coefficients of expansion, such as brass and invar, the strips being securely brazed or welded together lengthwise. It will be observed that the end of the member 15 remote from the fixed end is free to move vertically (Fig. 2) in response to changes in temperature.

Provided in the terminal block 11 is a vertically extending recess 11a which is adapted to receive an adjusting screw 17 which has a rounded end portion 18 which is adapted to bear against the member 15 near its fixed end. The adjusting

screw 16 is threadedly mounted in a transversely extending U-shaped bracket 18 secured to the base member by means of rivets (not shown), the threaded support being obtained by means of an internally threaded bushing 19 which is mounted in a suitable opening centrally located in the bracket 18. Located between the terminal block 11 and the bracket 18 is a sheet 20 of suitable electrically insulating material such as mica or a suitable phenol condensation product.

It will be understood that the bimetallic member by reason of its elasticity is forced upward into engagement with the end 17 of the adjusting screw and, as will more fully appear hereinafter, the temperature at which the control device is operated may be altered by varying the position of the end of the adjusting screw with respect to the base member 10.

Provided on the movable end of the bimetallic bar 15 is a knife-edge bearing 21 and between this bearing and a bearing 22 secured in a vertically extending integrally formed flange 23 on the base member 10 is interposed a coil spring 24. As illustrated, the spring 24 extends between two cups 25 and 26. The cup 25 is provided with a centrally located depression 27 which receives the knife-edge bearing 21 on the member 15 and the cup 26 is provided with a similar depression 28 which receives the bearing 22. The bearing 22 rather than being formed as a knife-edge has a pivotal or substantially conical form as clearly shown in Figs. 2 and 3 and the seat formed in the cup member 26 is shaped to conform to this bearing. The spring 24 preferably will be formed of a suitable moisture resistant material such as stainless steel.

The bearing pivot 22, as shown, is mounted upon the end of a screw 29 which is threaded into the flange 23 formed in the base member 10. The screw 29 is provided with a slotted end 30 whereby the position of the screw and hence that of the pivot bearing 22 can be changed with an ordinary screw driver or similar instrument. The screw 29 is secured in its adjusted position by means of a lock-nut 31. It will be observed that in view of this construction the position of the bearing 22 can be readily adjusted relative to the bearing 21 on the bimetallic member so as to change the tension in the spring member 24. The screw 29 and its lock-nut 31 are formed of steel rendered corrosive-resistant by cadmium plating.

The function of the pivotally mounted resilient member 24 described above is to move the bimetallic strip 15 quickly between its controlling positions and by adjusting the position of the pivot 22 to vary the tension of the resilient member 24, the end thrust exerted by the resilient member on the bimetallic strip may be varied and the character of the snap action as well as the amplitude or range between the maximum and minimum temperatures at which the device operates may be controlled.

Arranged to be actuated in accordance with movement of the bimetallic member is a pivotally mounted control arm, indicated generally by the numeral 34, which is spaced above the bimetallic strip 15 and extends in substantially the same direction as the strip. The control arm is pivotally mounted on a substantially U-shaped bracket 33 which overlies the bimetallic member, as shown in Fig. 2, and extends transversely of the base member as shown in Fig. 1, the bracket being secured to the base member 10 by means of rivets 32. The control arm 34 includes a metal-

lic frame 37 having a channel-shaped cross-section throughout the greater portion of its length. A shaft 35 is arranged to extend through the frame 37 and the leg portions of the bracket 33 to effect the pivotal mounting of the arm and the ends of the shaft 35 are flattened to maintain them in their assembled relation with respect to the bracket 33.

Also included in the control arm structure is a block of insulating material 38 which is firmly attached to one end of the frame 37 by means of suitable rivets 39. As will more fully appear hereinafter, the block of insulating material 38 is adapted to support a movable contact member which is arranged to engage fixed contacts so as to control an electric circuit.

In order to control the contact pressure between the movable contact carried on the control arm and the fixed contacts associated therewith and in order to abruptly actuate the movable contact member with a snap action, resilient means are provided which are separate and distinct from the resilient means provided for effecting movement of the bimetallic strip with a snap action. In mounting these resilient means, there is provided on the end of the member 37 remote from the end to which the block 38 is attached a knife-edge bearing 40 having a construction similar to the knife-edge bearing 21 provided on the bimetallic strip 15. Between this bearing 40 and a bearing 41 secured to the flange 23 is interposed a second resilient member 43. As shown, this resilient member 43 is a coil spring somewhat smaller in size than the coil spring 24 and extends between a pair of cup members 44 and 45 having recesses 46 and 47 adapted to receive, respectively, the bearings 40 and 41. The bearing 41 is substantially conical in form and is mounted on the end of a screw 48 similar to screw 29. The screw 48 is provided with a slotted end 49 whereby the position of the screw and hence that of the pivot bearing 41 may be adjusted longitudinally with respect to the base member 10.

The pivotally mounted control arm 34 and the pivotally mounted resilient means associated therewith substantially resemble a toggle mechanism and since a toggle mechanism depends upon the definite center line for snap action it is necessary to provide a vertical adjustment for the pivot bearing 41 so that the mechanism connected thereto can be arranged for equal displacements on each side of the center line. This vertical adjustment is achieved by means of a slot 51 which is provided in the upper end of the flange 23 and adapted to receive the screw 48. Referring to Fig. 1, it will be observed that the upper end of the flange 23 has a substantially U-shape over a distance slightly greater than the length of the slot 51. Threadedly supported on the screw 48 is a screw plate 52 which is adapted to be inserted into the channel formed by the upper U-shaped end of the bracket 23. By means of this construction, the screw 48 and hence the pivot bearing 41 may be adjusted vertically with respect to the base member 10. Suitable means comprising the lock-nut 50 bearing on the washer 53 is provided for holding the screw 48 and the bearing 41 in their vertically and longitudinally adjusted positions.

Arranged to transmit the motion of the bimetallic strip 15 to the control arm 34 is a link 54. As shown in Fig. 6, this link is provided with a pair of slots 55 adjacent one end and a pair of slots 56 adjacent its other end. Provided in

the member 37 is a transversely extending key-shaped opening 57 having a portion 57a sufficiently wide to permit the unobstructed movement thereto of an end of the link 54 and a second portion 57b sufficiently wide to permit the unobstructed longitudinal movement thereto of the portion of the link lying between the individual slots of the pair of slots 55. Provided in the member 15 adjacent the movable end thereof is a longitudinally extending key-shaped opening 58 located so as to lie below the opening 57 provided in the member 37. The opening 58 is sufficiently long to permit the lower end of the link 54 to be inserted thereto and is provided with a circular portion 58a having a diameter greater than the width of the portion of the member 54 lying between the individual slots of the pair of slots 56. In assembling the link in its operative position, the lower end thereof is inserted into the elongated opening 58 sufficiently far to permit the pair of slots 56 to lie opposite the surface of the member 15. The link is then moved longitudinally into the circular portion 58a of opening and is rotated through an angle of substantially 90° whereby it is locked in position insofar as its connection with the member 15 is concerned. The opposite end of the link is then inserted into the opening 57a until the slots 56 lie opposite the surface of the member 37. The link is then moved longitudinally so that the portion thereof lying between the individual slots of the pair of slots 56 is moved into the portion 57b of the opening. A washer 59 is then placed adjacent the link 54 and is firmly attached to the member 37 by means of a screw 60 which is adapted to be threaded into an opening 60a provided in the member 37 adjacent the opening 57. It is to be observed that the pairs of slots 55 and 56 of the link 54 are somewhat wider than the thickness of either the member 15 or the member 37 so that a certain amount of play exists in the connection between the member 15 and the link 54 and the control arm 34 and the link. This play permits the member 15 to be moved a small distance vertically without effecting any movement of the member 37.

As previously pointed out, there is mounted on the end of the member 37 an insulating block 38 made of some suitable insulating material such as Bakelite. Supported in the block 38 on its free end is a bridging contact assembly which is arranged to engage sets of fixed contacts 61 and 62 respectively arranged in pairs. As more clearly shown in Figs. 2, 3 and 4, the bridging contact assembly comprising a bridging contact plate 64 which is rotatably mounted upon a pin 65 which is molded into the insulating block 38. The rotation of the movable contact plate 64 is limited by a projection 66 which extends into a slotted section 67 provided in the insulating block 39. As will be observed from the drawing, the axis of rotation of the bridging contact plate lies substantially perpendicular to the pivot axis of the control arm 34. This permits freedom of action of the bridging contact plate in two planes at right angles to each other, thus assuring proper alignment of the bridging contact plate 64 with the sets of fixed contacts 61 and 62 so as to properly perform a switching function. The bridging and fixed contacts preferably will be formed of brass.

The fixed contacts 61 are rigidly secured to terminals 68 which in turn are firmly secured to the block 11 by means of rivets 69. Suitable binding screws 70 with which electrical connec-

tions are made are secured to the terminals 68. In a similar manner, the fixed contacts 62 are secured to the terminals 71 which are secured to the insulating block by means of rivets 72, suitable binding screws 73 being secured to the terminals 71. The terminals and binding screws preferably will be formed of brass and electrical connections are made therewith by directing suitable leads or conductors under the binding screws 70 and 73.

A suitable cover member 74 is provided for enclosing the operative elements of my improved control device. This cover member is adapted to rest inside of the flange 75 provided on the base member 10 and is secured in position by means of drive screws 76 which are received in apertures provided in the block 11.

The cover member 74 is provided with an aperture 77 through which is adapted to extend the vertically extending abutment 78 integrally formed on the insulating block 11 which, as shown in Figs. 2 and 3, projects through the aperture for a relatively short distance. In addition, the upper end of the adjusting screw 16 projects through the opening 77, the projecting portion of the adjusting screw being provided with a slot 79 for receiving an ordinary screw driver or similar instrument whereby the adjustment of the screw 16 can be effected conveniently.

Secured to the upper end of the adjusting screw is an index or pointer 80 which cooperates with a suitable temperature scale (not shown) arranged on the upper surface of the cover 74 so as to assist in making the temperature settings. The abutment 78 is arcuate in form and is provided with relatively flat side portions 81 which act as stops for the index pointer 80 at the lower and upper limits of its temperature setting so that it is impossible to move the adjusting screw beyond its normal range of operation, that is, beyond the upper and lower limits of the temperature range of operation of the device. This is important because it prevents the attendant from moving the adjustment beyond this normal range thereby preventing adjustments of the device which would destroy its calibration.

As illustrated in Figs. 2 and 3, the cover 74 is lined with an electrically insulating sheet 82 which may be made from a suitable phenol condensation product. It will also be observed that there is provided on the top of the cover member 74 a removable member 83 which is secured to the cover by means of the tongue and slot construction 84 and screws 85. This removable member 83 is adapted to serve as the nameplate upon which the temperature indicia as well as other nameplate material may be printed.

The base member 10 is provided with a plurality of apertures 86 through which suitable screw fastening means (not shown) may be passed to secure the base in good thermal relation with the body whose temperature is to be controlled. Thus, for example, the base may be secured to the side walls of a water heater storage tank whereby the thermally responsive member 15 is caused to respond to the temperature of the water.

In describing the operation of my improved control device, it will be assumed that the temperature adjusting screw 16 has been adjusted to maintain a predetermined temperature and that the elements of my device are in the position shown in Fig. 2. It will be observed that

the movable contact 64 engages the fixed contact 61 so as to bridge these contacts and close the circuit controlled by them. It will also be observed that the resilient member 43 is in a position to exert a downward thrust on the end of the frame 37 thereby maintaining a positive contact pressure between the fixed and movable contacts. So long as the temperature of the device which is being controlled is below the predetermined temperature for which the control device is set to operate, the movable contact member will be maintained in engagement with the fixed contact 61.

As the temperature of the device which is being controlled, a water heater, for example, increases, heat is transmitted to the bimetallic element 15 and causes this element to move upwardly against the force of the resilient member 24. The initial movement of the bimetallic element is very slow and is called creep. This creep of the bimetallic element, if transmitted to the control arm, would tend to decrease the contact pressure between the movable and fixed contacts. In accordance with my improved arrangement, the bimetallic element is permitted to creep but the means for transmitting the movement of the bimetallic element to the control arm which actuates the contacts is constructed so that the creep movement of the bimetallic element is not transmitted to the control arm. In other words, by means of the play purposely provided in the connection between the link 54 and bimetallic member 15 and control arm 37, the free end of the bimetallic member 15 may move or creep without causing any change in the control pressure between the movable contact and either of the pairs of fixed contacts 61 or 62 until snap occurs. Furthermore, it is to be observed, therefore, that by means of the play purposely provided in the transmitting means any tendency of the contacts to be altered by the creeping movement of the bimetallic element 15 is eliminated without in any way altering the adjustment of the spring 24 and hence without affecting the amplitude of the temperature responsive device. As a matter of fact, with my improved transmission system and the independent control arm structure, it is possible to decrease the force exerted by the spring 24 on the free end of the bimetallic blade without affecting the contact pressure thereby decreasing the operating temperature amplitude of the device, that is, decreasing the range between the maximum and minimum temperatures at which snap action occurs for any given temperature setting and hence increasing the switch sensitivity.

The play purposely provided in the transmitting means between the bimetallic member 15 and the toggle system is not only sufficient to substantially prevent variation in contact pressure until snap occurs but it also permits the bimetallic member to accelerate before any motion is transmitted to the control arm toggle system. Thus, when the temperature of the body being controlled attains the predetermined maximum temperature for which the control device is set, the bimetallic element 15 will have moved upwards until the restraining force of the resilient member 24 is relieved. The element 15 then accelerates in an upward direction and with the restraining force of the resilient member continually decreasing the acceleration is rapid and snap occurs. During this rapid acceleration, the play in the connection between

the link 54 and the members 15 and 37 to which the link is connected is taken up and the movement of the bimetallic blade is transmitted to and imparts a kick or thrust on the arm 37 and the control arm toggle system 34 is abruptly displaced from one stationary position, through its definite neutral position, and to its other stationary position thereby causing the movable bridging contact to be moved into engagement with the pair of fixed contacts 62.

It is to be observed that the member 37 is rotated about the shaft 35 provided in the bracket 33 when actuated by the force transmitted thereto by movement of the bimetallic member 15. By means of the resilient member 43, the rotation of the member 37 about this axis is accelerated once movement is started in a given direction thereby causing the movable contacts associated with the member to be moved quickly and with a snap action. In operation, therefore, the switch arm and its associated resilient member 43 move in a manner similar to an independent toggle mechanism which is actuated between two positions by means of a force exerted thereon, in this instance a force created by the snap movement of a temperature responsive element.

When snap occurs the component elements of my control device assume the position shown in Fig. 3. It will be observed that the resilient member 43 has been moved to a position so as to exert a thrust on the member 37 which tends to maintain a positive contact pressure between the movable contact 64 and the fixed contact 62. The spring 43 will hold the contact 62 closed until the temperature of the device which is being controlled is lowered to a predetermined minimum temperature. When the predetermined minimum temperature is obtained, the member 15 will be snapped downward thereby imparting a kick to the control arm toggle system 34 and effecting movement of the movable contact 64 to the position shown in Fig. 2. By means of the play in the connection between the member 37 and the member 15, no variation in contact pressure will occur as the bimetal strip 15 slowly cools, the operation of the device upon cooling being substantially the same as that upon heating.

It is apparent that the fixed contacts 61 and 62 act as stops to limit the movement of the movable contact member. The tension in the spring 43 is so adjusted that the movable contact member will strike the fixed contacts with sufficient force to break through any dirt or foreign matter collected thereon and thereby establish a good electrical contact. Since the control arm 34 and the resilient member 43 associated therewith for effecting its action function substantially the same as a toggle mechanism, the closing force with which the movable contact member strikes the fixed contact 61 will be the same with which it strikes the contact 62 and this closing force will be maintained substantially constant so long as the tension on the spring 43 is unaltered.

As pointed out previously, the temperature setting of the control device is adjusted by changing the position of the rod 16 relative to the element 15. The amplitude of the device on the other hand, that is, the range between the maximum temperature at which the bimetallic element moves to cause the opening of the contact 61 and the closing of the contact 62 and the minimum temperature at which the bimetallic member 15 moves to cause the opening of the

contact 62 and the closing of the contact 61, is affected by changing the position of the fixed bearing 22 to control the force exerted by the spring 24 on the free end of the bimetallic element 15. It is desirable to maintain the amplitude which is as small as practicable and this amplitude is determined by the spring force required to insure a positive snap movement of the bimetal blade 15.

In order to vary the contact pressure between the movable and fixed contacts, the fixed bearing 41 may be longitudinally adjusted to vary the tension of the resilient member 43. By moving the fixed bearing to the right, as shown in Fig. 2, the tension is increased thereby increasing the lateral thrust which the resilient member exerts on the knife-edge bearing of the arm 37 and thus increasing the contact pressure.

While I have illustrated my improved control device as having two pairs of fixed contacts to provide a double-pole contact structure, it is obvious that it could be readily adapted to a single-pole structure by the substitution of a suitable stop for one of the pairs of fixed contacts.

While I have shown a particular embodiment of my invention, it will be understood, of course, that I do not wish to be limited thereto since many modifications may be made, and I, therefore, contemplate by the appended claims to cover any such modifications as fall within the true spirit and scope of my invention.

What I claim as new and desire to secure by Letters Patent of the United States, is:

1. In a temperature control device, switch means, temperature responsive means, elastic means associated with said temperature responsive means to cause a snap action movement thereof upon the occurrence of a predetermined temperature, and means for actuating said switch means in accordance with movement of said temperature responsive means, said means including motion transmitting means located between said switch means and said temperature responsive means and loosely connected to each so as to provide a small amount of movement of said temperature responsive means relative to said switch means prior to said snap action movement of said temperature responsive means.

2. In a temperature control device, a resilient bimetallic strip clamped at one end and having its opposite end free to move, pivotally mounted elastic means bearing on said free end of said strip to cause said strip to be actuated quickly and with a snap action, switch means having a fixed contact structure and a movable contact structure, resilient means bearing on said movable contact structure for effecting a positive contact pressure between said fixed and movable contacts, and means for actuating said movable contact structure in accordance with movement of said bimetallic strip, said last mentioned means including a link loosely associated with both said movable contact structure and said strip so that said contact pressure between said movable and fixed contacts is substantially unchanged until said strip is actuated with a snap action by said elastic means.

3. In a control device, a support, a thin resilient bimetallic strip clamped on said support so as to have one end free to move, pivotally mounted resilient means bearing on said free end of said strip to cause said strip to be actuated with a snap action, a pivotally mounted control arm spaced above said bimetallic strip and extending in substantially the same direction as

said strip, switch means having fixed contacts and a movable contact adapted to be actuated by said control arm, pivotally mounted resilient means arranged to bear on said control arm to cause it to be moved quickly between two limiting positions so that said contact means are actuated with a snap action, means for varying the condition of said resilient means so as to alter the contact pressure between said movable and fixed contacts, and link means for transmitting the movement of said bimetal strip to said control arm so that the snap action movement of said strip imparts a kick to said control arm to cause said arm to be actuated, said link means being loosely associated with both said arm and said bimetal strip so that the initial slow movement of said bimetallic strip is not transmitted to said control arm.

4. In a control device actuated in accordance with changes in temperature, a bimetallic strip, elastic means associated with said bimetallic strip for causing it to be actuated with a snap action, means for preselecting the temperature at which said bimetallic strip is actuated with said snap action, control means independently mounted with respect to said bimetallic strip and extending in substantially the same direction as said strip, elastic means associated with said control means for causing said control means to be actuated with a snap action, and a link interconnecting said control means and said bimetallic strip whereby the snap action movement of said strip imparts a force to said control member to cause it to be actuated with a snap action, said link having slots therein for loosely connecting it to both said strip and said control means so that small movements of said strip prior to the occurrence of said predetermined temperature are not transmitted to said control member.

5. In a control device, a pivoted control arm having an opening adjacent one of its ends, switch means actuated by said control arm, elastic means associated with said control arm for moving said arm quickly so that said switch means are actuated with a snap action, a thermally responsive member having one end fixed and the other end free to move and having an opening therein adjacent said free end, elastic means associated with said free end to cause said thermally responsive member to be moved with a snap action, and means extending through said openings in said control arm and in said temperature responsive member for transmitting the movement of said member to said arm, said means being constructed and arranged so that said bimetal member moves a small amount independently of said control arm.

6. In a control device, a pivoted control arm having an opening adjacent one of its ends, switch means actuated by said control arm, elastic means associated with said control arm for moving said arm quickly so that said switch means are actuated with a snap action, a thermally responsive member having one end fixed and the other end free to move and having an opening therein adjacent said free end, elastic means associated with said free end to cause said thermally responsive member to be moved with a snap action, and a link for transmitting the movement of said thermally responsive member to said control arm so that said control arm is moved to actuate said switch means in accordance with temperature changes, said link being loosely supported in said openings provided in said control arm and said thermally responsive

member so that said thermally responsive member may move a limited amount relative to said control arm.

7. In a control device, a control arm pivoted intermediate its ends and having an opening adjacent one of its ends, switch means actuated by said control arm, pivotally mounted elastic means bearing on said control arm for moving said arm quickly so that said switch means are actuated with a snap action, a bimetallic member spaced from said control arm and having one end fixed and the other end free to move, said bimetallic member having an opening therein located so as to be in substantial alignment with said opening in said control arm, elastic means associated with said free end of said bimetal member to cause said member to be moved with a snap action, a link extending through said openings in said arm and in said bimetal member for transmitting the movement of said bimetal member to said arm so that said switch means are actuated in accordance with temperature changes, said link having a pair of slots adjacent each end thereof which slots are constructed and arranged to permit a limited amount of play in the connections between said link and said bimetal member and said link and said arm so that said bimetal member may move a small amount independently of said control arm.

8. In a control device, a bimetallic temperature responsive member fixed at one end and having its opposite end free to move, elastic means associated with said free end and arranged to cause said temperature responsive member to move quickly and with a snap action, means for adjusting the temperature at which said temperature responsive member is actuated by said elastic means, a bracket overlying said temperature responsive member, a control arm pivoted intermediate its ends on said bracket, a contact member attached to one end of said control arm, elastic means bearing on the opposite end of said control arm for causing it to be moved with a snap action, fixed contacts arranged to be engaged by said contact member so as to perform switching functions, a link lying between said thermally responsive member and said control arm and connected thereto to cause said switching functions to be performed in accordance with movement of said thermally responsive member, said link having slots therein adjacent its connection to said thermally responsive member to permit limited movement of said temperature responsive member in accordance with temperature changes independently of said control member.

9. In a temperature control device, a support, a bimetallic temperature responsive element mounted on said support and having one end free to move, elastic means associated with said free end of said bimetallic member to move said member quickly and with a snap action upon the occurrence of a predetermined temperature, means for adjusting said predetermined temperature at which snap action occurs, a bracket mounted on said support and adapted to extend above said bimetallic member, fixed contacts mounted on said support, a control arm pivotally mounted on said bracket, elastic means associated with one end of said control arm to move said arm quickly and with a snap action, movable contact means associated with the other end of said control arm and adapted to cooperate with said fixed contacts to perform a switching function, and a link interconnecting said bime-

tallic member and said control arm whereby the movement of said bimetallic member with a snap action imparts a thrust to said control arm to cause movement thereof, said link having a pair of recesses adjacent each end thereof which are adapted to cooperate with said bimetallic member and said control arm, respectively, to form a loose connection therebetween whereby movement of said bimetallic member prior to said snap action movement is not transmitted to said control arm.

10. In a control device, a pivotally mounted control arm, fixed contacts, a movable contact adapted to be actuated by said control arm, pivotally mounted elastic means bearing on one end of said control arm, means for adjusting said elastic means so as to control the contact pressure between said movable and fixed contacts, means for controlling the position of said elastic means so that said control arm will be moved with a snap action equal distances above and below a line passing through the pivots of said elastic means on said control arm, a temperature responsive element spaced from said control arm, and means loosely connected to both said temperature responsive element and said control arm for transmitting the motion of said element to said control arm so that after a predetermined movement of said temperature responsive element a thrust is imparted to said control arm to initiate pivotal movement of said arm whereby said arm is moved under the influence of said elastic means from one side of said line to the other so that said movable contact is moved into and out of engagement with said fixed contacts in accordance with the occurrence of predetermined temperatures.

11. In a control device having a support, fixed contacts mounted on said support, a movable contact adapted to cooperate with said fixed contacts to perform switching functions, a toggle system associated with said movable contact and adapted to cause said switching function to be performed with a snap action, said toggle system comprising a frame pivotally mounted on said support, means connecting one end of said frame to said movable contact assembly, a knife edge provided on the opposite end of said frame, a spring adapted to bear on said knife edge to move said frame quickly and with a snap action above and below a neutral line whereby said movable contact is moved with a snap action, a bearing for the opposite end of said spring, means for varying the position of said bearing longitudinally to vary the lateral thrust exerted by said spring on said knife edge, means for vertically adjusting said bearing to cause said frame to be moved equal distances above and below said neutral line, a thin resilient bimetallic member clamped on said support and having one end free to move, elastic means for moving said free end of said bimetallic member quickly and with a snap action upon the occurrence of a predetermined temperature, means for adjusting and preselecting said predetermined temperature, means for transmitting the movement of said bimetallic member to said toggle system whereby said system and its associated movable contact are actuated in accordance with temperature changes, said last mentioned means including means imparting a kick to said toggle system when said bimetallic member is moved with a snap action, and means for providing a limited amount of free movement of said bimetallic element relative to said toggle

system whereby the initial slow movement of said bimetallic element is not transmitted to said toggle system.

12. In a control device a base member, a temperature responsive element mounted on said base member so as to have one end fixed and its opposite end free to move, a control arm, means for pivotally supporting said control arm on said base member, means for actuating said control arm in accordance with the movement of said free end of said temperature responsive member, elastic means for causing said control arm to move with a snap action after a predetermined movement of said temperature responsive element, a pair of fixed contacts, movable bridging contact means adapted to cooperate with said fixed contacts to perform a circuit controlling function, and means for rotatably mounting said bridging contact means on said control arm, said last mentioned means permitting limited pivotal movement of said bridging contact means about an axis substantially perpendicular to the axis about which said contact arm pivots so that upon actuation of said control arm said bridging contact means is free to move in two planes lying at right angles to each other to align itself with said fixed contact means to insure proper cooperation therebetween for performing said circuit controlling function.

13. In a control device a base member having a transverse axis and a longitudinal axis, a temperature responsive element mounted on said base member so as to have one end fixed and its opposite end free to move, a pivot pin mounted on said base member so that its axis is substantially parallel to said transverse axis of said base member, a control arm, means for pivotally supporting said control arm on said pivot pin, means for actuating said control arm in accordance with the movement of said free end of said temperature responsive member, elastic means for causing said control arm to move with a snap action after a predetermined movement of said temperature responsive element, a pair of fixed contacts, a movable bridging contact adapted to cooperate with said fixed contacts to perform a circuit controlling function, and means for pivotally mounting said bridging contact near one end of said control arm so that it is free to pivot about

an axis parallel to the longitudinal axis of said base member, said pivotal movement of said control arm and said pivotal movement of said bridging contact producing freedom of movement of said bridging contact in two planes lying at right angles to each other so that said bridging contact plate aligns itself with said fixed contact means to insure proper cooperation therebetween for performing said circuit controlling function.

- 10 14. In a control device a base member having a transverse axis and a longitudinal axis, a temperature responsive element mounted on said base member so as to have one end fixed and its opposite end free to move, a pivot pin mounted on said base member so that its axis is substantially parallel to said transverse axis of said base member, a control arm, means for pivotally supporting said control arm on said pivot pin, means for actuating said control arm in accordance with the movement of said free end of said temperature responsive member, elastic means for causing said control arm to move with a snap action after a predetermined movement of said temperature responsive element, a double pole 25 fixed contact structure, a movable bridging contact member adapted to cooperate with said fixed contact structure to perform a circuit controlling function, a second pivot pin mounted on one end of said control arm so that its axis lies substantially parallel to the longitudinal axis of said base member, means for rotatably mounting said bridging contact member on said second pivot pin, and means for limiting the rotation of said bridging contact member about said second pivot 30 pin so as to provide limited pivotal movement thereof about said pin, said pivotal movement of said contact arm about said pin having an axis substantially parallel to the transverse axis of said base member and said pivotal movement of 35 said bridging contact member about said pin having an axis substantially parallel to the longitudinal axis of said base member providing two degrees of freedom of movement of said bridging contact member in two planes lying at right 40 angles to each other to insure proper alignment between said bridging contact member and said double pole fixed contact structure for performing said circuit controlling function.

WALLACE J. ETTINGER.
